US0D1077267S

(12) **United States Design Patent** (10) **Patent No.:** **US D1,077,267 S**
(45) **Date of Patent:** **** May 27, 2025**

(54) **SPERM SAMPLER VIBRATOR**

(71) Applicant: **TENGA Co., Ltd.**, Tokyo (JP)

(72) Inventor: **Kyohei Takahori**, Tokyo (JP)

(73) Assignee: **TENGA CO., LTD.**, Tokyo (JP)

(***) Term: **15 Years**

(21) Appl. No.: **35/520,289**

(22) Filed: **Jan. 24, 2024**

(80) **Hague Agreement Data**

Int. Filing Date: **Jan. 24, 2024**

Int. Reg. No.: **DM/235637**

Int. Reg. Date: **Jan. 24, 2024**

Int. Reg. Pub. Date: **Mar. 15, 2024**

(30) **Foreign Application Priority Data**

Aug. 22, 2023 (JP) 2023-016884

(51) **LOC (15) Cl.** **24-01**

(52) **U.S. Cl.**

(57)

CLAIM

The ornamental design for a sperm sampler vibrator as shown and described.

DESCRIPTION

1. Sperm sampler vibrator

1.1 : Perspective

1.2 : Front

1.3 : Back

1.4 : Left

1.5 : Right

1.6 : Top

1.7 : Bottom

The portions of the figures converted to dashed lines do not constitute part of the claimed design.

(Continued)

A sperm sampler vibrator according to the present design is detachably attached to the sperm sampler and vibrates to the sperm sampler.

1 Claim, 7 Drawing Sheets
